US0D1017767S

(12) **United States Design Patent** (10) **Patent No.:** **US D1,017,767 S**
(45) **Date of Patent:** **** Mar. 12, 2024**

(54) **SPRAY GUN**

(71) Applicant: **Xiaogang Zhang**, Yangzhou (CN)

(72) Inventor: **Xiaogang Zhang**, Yangzhou (CN)

(**) Term: **15 Years**

(21) Appl. No.: **29/835,326**

(22) Filed: **Apr. 18, 2022**

(51) LOC (14) Cl. **23-01**

(52) U.S. Cl.

USPC **D23/226**

(58) **Field of Classification Search**

USPC D23/213, 223, 225, 226, 229, 245;
D8/68; D21/572, 573, 574

CPC B05B 9/00; B05B 9/01; B05B 7/02; B05B
12/00; B05B 15/00; B25F 5/00

(57) **CLAIM**

The ornamental design for a spray gun, as shown and described.

DESCRIPTION

FIG. 1 is a perspective view of a spray gun, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
